Primary Examiner — Brett Miller*Assistant Examiner* — Nader Abadir(74) *Attorney, Agent, or Firm* — Paul & Paul(57) **CLAIM**

The ornamental design for a glass, as shown and described.

DESCRIPTION

FIG. 1 is a side elevational view of a glass according to the present invention, the glass being rotationally symmetric so that the side elevational view is the same from all sides.

FIG. 2 is a perspective view of the glass of FIG. 1.

FIG. 3 is a top plan view of the glass of FIG. 1.

FIG. 4 is a bottom plan view of the glass of FIG. 1; and,

FIG. 5 is a cross-sectional view of the glass of FIG. 1 taken along the line 5-5 of FIG. 1.

1 Claim, 3 Drawing Sheets(56)
